UNITED STATES PATENT OFFICE.

DANIEL D. MADDEN, OF PORTLAND, OREGON.

IMPRINTING DEVICE.

Application filed November 30, 1925. Serial No. 72,270.

My invention relates to apparatus for making imprints as a class.

The object of my invention is to provide such a device particularly intended for imprinting labels and designs upon wrapping paper during the time the paper is being colored in a bath of coloring liquid, the apparatus having a roller provided with removable plates thereon adapted and arranged to allow the roller to make imprints and the paper to pass under the roller and under pressure so that it will emerge with three tints or shades. These objects, as well as other advantages, I attain by the construction, combination and arrangement of parts illustrated in the drawings which form a part hereof.

Fig. I is a front elevation of the imprinting roller with inserted plates and with parts broken away.

Fig. II is an enlarged sectional view of part of the roller and imprinting plates inserted in place, on the line II-II in Fig. I.

Fig. III is a detail plan view of the plate fastener in operative position.

Fig. IV is a side elevation of the plate fastener without locking pin.

Fig. V is a plan view of screw plug for fastener spring.

Fig. VI is a diagrammatical sectional elevation of the bath, paper transmission and my device in connection therewith, parts being in section.

Like characters refer to like parts in the views.

A frame 1 supports a tank 2 and the standards 3 and 4. In the standard 3 are guides 5-6, having oppositely disposed bearings 7-8 transversely positioned on each side of the tank and at convenient heights. In the lower bearings 8 a roller 9 of rubber or other material of like nature is rotatably mounted. Above said roller a second metal roller 10 is rotatably mounted. The rollers are slipped into their bearings and removed therefrom through the guides. A pulley 11 is connected with the shaft of the roller 9 when the same is in place, and a belt 12 extends from the pulley to a power source.

Above the journals of the roller 10 pressure screws 13 are arranged in the standard 3, with compression springs 14, to press the roller 10 to a desired engagement with the lower roller 9. In the roller 10 are plate receiving recesses 15, arranged in series about the roller. At each end of the recesses 15

are small recesses 16, threaded in their upper portions. A screw plug 17, having a longitudinal groove 18, is adapted to be screwed into the recess 16. A fastener 19, having a coil spring 20 on its lower portion and an eye 21 on its upper end, is slideable into the groove 18, adapting the spring portion of the fastener to be positioned in the recess 16 with the neck of the fastener extending above the plug, the spring engaging the lower surface of the plug and retaining the fastener eye upon the upper surface of the plates. Liners 22 are placed within the recess 15 to cause the plate surface to extend beyond the plane of the roller surface a predetermined distance. Imprinting plates 23 are provided, having a curvature in alignment with that of the roller. The plates have angled ends 24 and grooves 25 in each of these ends to admit the fastener eye 21 therein. When the plates are laid upon the liners in the recesses 15, pins 26 are inserted through the fastener eyes and the springs 20 then retain the pins in engagement with the plate ends and thus retain the plates in operative position on the roller. A marginal space is left between the upper plane edges of the plate 23 and the opposing walls of the recess 15. Rollers 10 with recesses 15 of varying dimensions are provided to receive plates of corresponding relative dimensions, bearing different imprinting characters and designs. In the standard 4 are mounted wringer rollers 27 of rubber and 28 of metal, with pressure screws 29 above, having compression springs 30 to force the said rollers into engagement. Near one end of the tank is a standard 31 adapted to receive the shaft 32 holding a paper roll 33. Guide rollers 34 are positioned to carry the paper from the roll 33 into the tank, to the imprint rollers, from them to the wringer rollers and from the latter to a drying place. A selected color fluid 35 is placed in the tank. The course of the paper through the apparatus is indicated by arrows in Fig. VI. The plates have integral engraved designs or characters in their surfaces, as illustrated in Fig. I, recessed in them.

The operation will now be described. A coloring liquid of any desired kind is placed in the tank, the level thereof being below the lower surface of the roller 10. The imprint forms of the plates are cut or recessed in them as stated. The plates 23 which are selected for the intended operation are placed over

liners in the recesses 15 in a manner to raise the surface of the plates slightly above the adjacent surface plane of the roller 10. The ends of the fasteners 19 slip through the plate 5 grooves 25 and the pins 26 are inserted in the fastener eyes 21, thus locking the plates on the roller. The roller 10 is then slipped through the guides to the operative position shown in Fig. VI. The paper is then drawn 10 from the roll about the guide rollers, through the rollers 9—10 and the wringer rollers 27—28, thence outwardly to a convenient drying place. Power being applied, the plates are impressed upon the paper with 15 greater penetration of its fibre than that of the adjacent surface of the roller. This causes the surface about the plate characters to become apparent in a darker shade than that part of the paper subjected to the pressure of the roller surface only. The marginal space about the plates prevents any pressure upon the paper which is immediately over said space, while passing the rollers. That portion of the paper, as also that above 20 the characters, thus remains without change from the color it assumes in the bath, which is lighter than that produced by the plate surfaces or rollers. Thus a margin is formed about the body color made by the plate surfaces and between the same and the body 25 color of the remainder of the paper as made by the roller surface. By the operation of my device wrapping paper is produced of varying beautiful tints or shades, bearing a series of imprints with margins about them containing advertising matter, designs, trade-marks, etc., all arranged in a most attractive form. The apparatus has been in practical operation and found to be entirely 30 successful in producing the paper described, which has been accepted and used by the public to a large extent. The operation of the device is very economical, as a few changeable rollers will accommodate an unlimited assortment of plates varying in dimensions. Heretofore rollers with imprints engraved in them have been commonly used, which makes the operation expensive. In 35 my device the plates are made at a minimum expense and thus greatly economize the operation to manufacture the paper mentioned. The single operation to produce three colors is highly advantageous in the art and trade. The device is therefore distinctively novel 40 and useful.

I claim:

1. Means for imprinting on paper a plurality of tones with one dye, comprising, in combination, means for holding a quantity 45 of dye, impression rollers, having varying impression surfaces, mounted in proximity to the dye in said dye holding means, means

for immersing paper in the dye and passing it directly from the dye to and between said rollers and directly from said rollers to and through said dye a second time.

2. Means for imprinting on paper a plurality of tones with one dye, comprising, in combination, means for holding a quantity of dye, impression rollers, having varying impression surfaces, mounted in proximity to the dye in said dye holding means, means for immersing paper in the dye and passing it directly from the dye to and between said rollers and directly from said rollers to and through said dye a second time, and means for applying pressure to said rollers.

3. Means for imprinting on paper a plurality of tones with one dye, comprising, in combination, means for holding a quantity of dye, impression rollers, having varying impression surfaces, mounted in proximity to the dye in said dye holding means, means for immersing paper in the dye and passing it directly from the dye to and between said rollers and directly from said rollers to and through said dye a second time, and wringer rollers between which the paper is passed after it leaves the dye.

4. A device for imprinting on paper a plurality of tones with one dye, comprising, in combination, a dye tank for holding a quantity of dye, a smooth surfaced roller of compressible material mounted in bearings in said tank in position to extend below the surface of the dye in the tank, a non-compressible roller arranged in contact with said compressible roller, and having varying impression surfaces, means for immersing paper in the dye in said tank and passing the same directly to and between said rollers and directly from said rollers to and through said dye a second time.

5. A device for imprinting on paper a plurality of tones with one dye comprising, in combination, a dye tank for holding a quantity of dye, a smooth surfaced roller of compressible material mounted in bearings in said tank in position to extend below the surface of the dye in the tank, a non-compressible impression roller mounted in movable bearings above and in contact with said compressible roller, and having varying impression surfaces, means to guide a web of paper below the surface of the dye and thence directly to and between said rollers, means to guide the paper after it passes between the rollers directly below the surface of the dye a second time, and means for holding the non-compressible roller with a heavy pressure against the compressible roller.

DANIEL D. MADDEN.
